FIG 1

FIG 2

FIG 3

FIG 4

FIG. 1 is a perspective view of a pocket billiard table or similar article.

FIG. 2 is a front elevational view thereof; and the appearance thereof in rear elevation is identical to that illustrated in FIG. 2.

FIG. 3 is an elevational view of one end thereof; and the appearance thereof at the opposite end is identical to that illustrated in FIG. 3.

FIG. 4 is a bottom plan view at one side thereof; and the bottom plan view at the other side is identical to that illustrated; the portion of the design illustrated in full lines would be invisible in the top, plan view with the exception of the outer periphery of the pocket billiard table.

The dominant feature of the invention is that portion shown in full lines in the drawings.

This is a continuation-in-part of design application, Ser. No. 7,752, filed July 10, 1967.

I claim:

The ornamental design for a pocket billiard table or similar article, as shown and described.
